SHIRT SLEEVE

Pete Petersen, P.O. Box 6231,
Hollywood, Fla. 33021

Filed June 14, 1974, Ser. No. 479,350

Term of patent 14 years

Int. Cl. D2—99

U.S. Cl. D2—452

Fig. 1.

Fig. 2.

Fig. 3.

Fig. 4.

Fig. 5.

FIG. 1 is a front and left side perspective view of a shirt sleeve showing my new design;

FIG. 2 is a top and left side perspective view in folded condition;

FIG. 3 is a view similar to FIG. 2 in partially opened condition;

FIG. 4 is a fragmentary top and left side perspective view in fully opened condition; and

FIG. 5 is a rear and right side perspective view in the condition of FIG. 1.

I claim:

The ornamental design for a shirt sleeve, as shown and described.
